UNITED STATES PATENT OFFICE

MARY D. NEILSON, OF MINNEAPOLIS, MINNESOTA

WOMAN'S VEST

Application filed July 14, 1930. Serial No. 467,817.

My invention relates to women's vests and has for its object to produce a simple and inexpensive vest which will fit itself readily and effectively to the form of the wearer and 5 wherein the fullness needed to accommodate the garment over the busts and over the hips is provided by a simple and effective means of cutting a closed elastic tube of woven or knitted fabric so that said tube will produce 10 the vest, forming at the same time a brassière and a slip.

The full objects and advantages of my invention will appear in connection with the detailed description thereof, and its novel features are particularly pointed out in the 15 claim.

In the drawing, illustrating the application of my invention in one form,—

Fig. 1 is a side view of a figure or manikin 20 showing the vest in position thereon. Fig. 2 shows the form of the vest when fabricated solely out of a tube. Fig. 3 is a cross-section of said tube which will preferably be of knitted or elastic material. Fig. 4 is a view of 25 said tube showing the manner in which the vest portions are cut therefrom. Fig. 5 illustrates a different form of cutting the tube to provide a garment having fullness over the hips. Fig. 6 shows the form of a filler strip 30 used in completing the garment of Fig. 5. Fig. 7 illustrates a tube blank showing the manner of cutting the tube to produce the blank pieces of Figs. 5 and 6. Fig. 8 is a manikin figure showing the completed garment 35 of Figs. 5 and 6 in position on the form of the wearer. Fig. 9 is a manikin figure showing the completed garment in position on the form of the wearer as worn under bloomers.

40 Knitted and elastic fabric is obtainable in quantity in the form of tubes such as shown at 10 in Figs. 3 and 4. It has been proposed to use such tubes for undergarments by cutting a right line across the same as shown at 11 in Fig. 3. Garments so constructed as 45 worn will not hang properly, bunching under the arms and inadequately covering the busts, and, if large enough to be worn comfortably over the hips, will be too large and 50 loose about the busts. I have discovered that

if the tube 10 is cut across in a broad reverse curve at top and bottom, as indicated at 12 in Fig. 4, then a simple tubular garment as indicated by the numeral 13 of Figs. 1 and 2 will be produced. By attaching shoulder straps at the sides of the upper edges 14 of the cuts 12, as indicated in Fig. 1, the tubular garment will be suspended from the shoulders so that the back portion 55 will be lower and the front portion lifted 60 to cover the busts, and the garment will be compact, inexpensive and satisfactory in use.

A better fitted garment which at the same time has the effect of being both slip and brassière is shown in Figs. 8 and 9. Blanks 65 are cut for this garment as illustrated at 16 in Fig. 5. In this form the blanks are cut in pairs from the tubes 10, the outer cuts 17 of each pair being similar to the cuts 12. At the middle of the tube the pairs are divided 70 as shown in Fig. 7 by means of a convex cut 18 running to the center of the tube 10 as compared with a concave cut 19 running from the other edge to the center of the tube 10, and said tube is cleft at its center as 75 indicated at 20 a suitable distance. The cuts 18 and 19 are offset as indicated at 21, and since the cleft 20 is along the longitudinal center of the tube, this offsetting will be symmetrical as to each piece of the pair. Triangular pieces 22, shown in Figs. 6 and 7, are cut out of a portion of the tube, a dozen such triangular pieces being cut with little waste from a short section, as shown in Fig. 7. These triangular pieces 22 have a short side 80 23 and a long side 24, the short side being sewed to the shorter portion of the longitudinal cleft 20, as indicated at 25 of Fig. 8; and the long side being sewed to the longer portion of said cleft at 26. The end of the 85 triangular piece 27 is trimmed to match the curves 18 and 19 so that the finished garment will have a bottom curve similar to the curve 12 of the simple tubular garment. There will, of course, be a cleft 20 on each side of the garment indicated at 28 and piece 22 90 sewed into each side of the garment, and when this construction is employed a tube may be used small enough to act in its upper portion as a brassière while its lower portion 100

will be sufficiently enlarged to fit comfortably over the hips of the wearer. If desired the front of the garment between the busts may be gathered to effect better fit, as indicated at 29 in Fig. 9.

The advantages of this construction will be very apparent. There is no waste at all where the simple tube garment 13 is constructed, and substantially no waste where 10 the brassière fulled garment 28 is constructed. The garment will be strictly form-fitting in the latter case and form-fitting to a degree in the former case. Owing to the manner in which the tube is cut across, the garment will 15 hang from shoulder straps very satisfactorily, and it is in every way economical to manufacture, and, hence, can be sold at a reasonable price.

I claim:

- 20 A fitted vest comprising a section of a tube of knitted or elastic material of uniform cross-sectional diameter thruout its length cut across at top and bottom with parallel reverse curves such that the front of the resulting garment will extend up higher on the body of the wearer than the back and the garment will fit the wearer without pulling or bunching, said cuts at the bottom of said tube being offset along the longitudinal 25 centers of the sides and the tube being cut in an extension of said offset lines, and a triangular piece being sewed into said side cuts to form a continuation of the bottom edge of the garment and increase its diameter 30 35 about the hips of the wearer so that the upper portions of the garment may be small enough to act as a brassière.

In testimony whereof I hereunto affix my signature.

40 MARY D. NEILSON.
